UNITED STATES PATENT OFFICE.

HENRY JAMES BICKLE, OF GLADSTONE, MANITOBA, CANADA, ASSIGNOR OF ONE-FOURTH TO MAGNUS WILSON AND ONE-FOURTH TO MALCOLM McMILLAN, OF GLADSTONE, CANADA.

SCRAPER.

No. 866,615.

Specification of Letters Patent.

Patented Sept. 24, 1907.

Application filed November 28, 1906. Serial No. 345,520.

To all whom it may concern:

Be it known that I, HENRY JAMES BICKLE, of the town of Gladstone, in the Province of Manitoba, Canada, inventor, have invented certain new and useful 5 Improvements in Scrapers, of which the following is the specification.

My invention relates to scrapers, more especially wheeled scrapers, and the objects of the invention are to provide, firstly, a scraper with a swing lift pan completely under the control of a single operator, and in which the draft animals supply all the necessary energy for dumping, secondly, to provide a scraper which allows that the draft animals may remain continuously on the road bed while operating, thirdly, to provide a 15 scraper which will practically eliminate all unnecessary heavy neck work or undue strain on the draft animals, and lastly to provide a novel locking device for retaining the pan in several operative positions, the parts being arranged and constructed as hereinafter 20 more particularly described.

Figure 1 is a perspective view of my complete invention; the pan locked in the upper position. Fig. 2 is a side elevation of the scraper; the pan locked in one of the lower positions. Fig. 3 is a side elevation of the 25 scraper; the pan in a dumping position, being freed from the locking bar. Fig. 4 is a plan view of the scraper, the pan being unlocked previous to dumping. Fig. 5 is a side elevation of a second embodiment of my invention. Fig. 6 is an enlarged, detailed, perspective view, showing the wheel spindles, the pan suspending bar, and a broken portion of the frame or side bars, to which the draw bar is secured. Fig. 7 is an enlarged, detailed, perspective view of a portion of the draw bar and the lock bar. Fig. 8 is an enlarged, detailed, 30 perspective view of the means employed for securing the tongue to the draw bar. Fig. 9 is a side view showing the bail bar on the scoop.

Heretofore it has been the practice when dumping the pan, that several men lift on a pair of handles, secured, one at each side of the pan, and consequently much extra labor was involved. I consider it one of the prime features of my invention, that the pan is pivotally suspended by a bar, fastened rearwardly and below the center to the sides, and not as ordinarily employed by a bar secured rigidly to the pan. Suspension in this manner gives me an added moment, and the swing lift, which is used to advantage.

A A are the carriage wheels and B the pan which is of the ordinary form. 50 C is the bar suspending the pan and has its extending ends C¹ C² bent substantially at right angles to the body and flattened.

C³ are the stub axles for the carriage wheels secured one at each side, to the portions C¹ C², and upwardly

towards the angle in the bar. It will be understood 55 that the axles are normally horizontal.

D D¹ are bolts passing through the lower end of the portions C¹ C², and through the side faces of the scraper, and are retained in position by nuts in the ordinary manner. As pointed out above, the bolts pass through 60 the pan rearwardly and below the center of the sides.

E E¹ are side bars which form practically the framework of the scraper. They are pivoted at their front end at the base of the axles C³ and pass rearwardly, being bent inwardly around the back of the scraper, and 65 then rearwardly, forming a side plate, to which is secured the front end of the push or drag bar E², by bolts E³.

F are braces, one on each side, secured across the angle of the bar E.

The drag or push bar E² is hollow, and has a slidable 70 rod or locking bar F² passing centrally therein. The drag bar has a portion G cut away from its upper side, as clearly shown in Fig. 7, and the adjoining end of the drag bar is open. The lock bar also has a portion cut away, the cut enlarging from the top inwardly, forming 75 a recess with acute angled ends G².

H is a flat bar of a V-shape, having its ends flanged, and secured to the rear of the pan by bolts H¹. The angle of the V-shape is squared at H², in order that it may pass more readily into the incision G¹ in the locking bar. The thickness of the bar H is such, that when 80 in the incision G¹ its upper face is below the surface of the level of the locking bar. It is to be understood that the width of the bar H is such that it can easily clear from the opening in the bar F².

I I are braces passing obliquely downwardly from the upper edge of the rear of the pan, and attached to the V-shaped bar on either side of its center.

The rear end I¹ of the drag bar E² is flattened somewhat, in order to form a bearing surface for a circle and 90 several other attachments, and has an opening I² cut longitudinally and centrally therein.

J is a plate secured to the side face of the drag bar, and J¹ is a toothed quadrant secured to the other side of the bar and directly opposite the plate J.

K is a shaft extending across the end of the drag bar above the opening I² and bearing at either side within the plate J and the quadrant J¹ respectively.

K¹ is an arm secured rigidly to the shaft and passing 100 downwardly therefrom, its lower end being connected by means of a rod K² to the locking bar F².

L is a handle or lever attached to the end of the shaft K and is provided with a hand latch L¹, operating detents co-operating with the notches in the arch in order to secure said lever in any desired position on the arch 105 or quadrant. The quadrant may be completely toothed, but it is only necessary to have a sufficient number of teeth to be able to hold the lever in three positions, for

convenience in operating it is preferable to have the lever with the lower end turned somewhat out of alignment with the body, such allowing that the lever is never thrown farther forward than the vertical position.

5 M is a circle with its edges flanged or turned outwardly, the said circle having wings M¹ securing it to the end of the draw bar.

M² is an annular ring enveloping the body of the circle M and retained thereon by the flanges, and has a rear 10 extension M³ to which is secured the seat spring N, in turn supporting the seat N¹.

N² is a portion extending forwardly from the ring and to which is secured a tongue O by means of a side plate O¹ secured to the rear end of the tongue and pivotally 15 connected with the extension N² by a bolt O². In this way the tongue is able to turn completely around carrying with it the seat. A broken portion of the tongue, extending in a position forward of the drag bar, is shown in Fig. 1, while the other elevation figures show the 20 tongue over the drag bar.

P is a swivel wheel below the rear end of the drag bar, directly under the control of a hand wheel P¹, readily operated from the seat in all positions.

The three required positions of the lever L are the 25 vertical, the horizontal, and one practically midway between. These various positions are shown respectively in Figs. 1, 2, & 3, and the corresponding positions of the pan for these positions is also shown.

Assume the locking bar F² to be in the position, as 30 shown in Fig. 7, relative to the drag bar, such being when the lever L is in the intermediate position, between the vertical and horizontal. In this case the portion H² of the bar H is free to drop into or clear from the incision G¹. Assuming further that the pan is, as 35 shown in Fig. 4, that is with the portion H² resting in the incision. Upon throwing the lever to the horizontal, (see Fig. 2) the pan is swung downwardly, till the tip comes to the ground level. This is caused by the edge of the bar H coming in contact with the slant face

40 G² of the lock bar, and being forced forwardly by the forward movement, due to the lever. When the locking bar is in such forward position the portion H² of the bar H is retained or locked within the incision G¹ by means of the overhanging lip Q of the drag bar, and 45 consequently it is impossible for the pan to move from its position. Upon bringing the lever L to the vertical position (see Fig. 1), the bar H is carried rearwardly by the notch in the locking bar, and the pan is lifted clear of the ground level and retained in its position by a 50 lock similar to that above described; the portion H² being held in position by the other slant side G² of the lock bar and the overhanging portion Q¹ of the drag bar.

From the above description it will be seen that the 55 pan can be locked by the operator in two positions, and released at will, the whole being under the control of the lever L, and to better understand the features of the machine its operation in use is hereinunder described.

60 A team is attached by the usual doubletree and neck yoke to the tongue O, and the operator takes his place on the seat. When it is required to fill the pan the team is turned around facing the pan, the tongue being then in a position directly above the drag bar. The 65 operator throws the lever downwardly to the horizontal

position, which throws the pan with the tip to the ground, and locks it there (see Fig. 2). As ordinarily employed in scrapers when filled, a snatch team is used, and it is attached to a bail bar R, which is pivoted to the pan by pins R¹ on either side thereof. As 70 shown the bar is bowed and passes across the front of the pan. R² is an arm attached to the bail bar and R³ a spring which passes from the arm to a pin on the pan. R⁴ is a ring to which a rope from the whiffle-tree of the snatch team is attached. The position of the front 75 portion of the bail is directly below the drag bar. In this way, it will be noted, that it is impossible for the pan to fly up, or turn over, as it is locked in position. After the pan has been filled, the snatch team is taken off, the lever is thrown to the vertical position and the 80 pan raised clear of the ground and locked in that position. When it is required to dump, the lever is thrown to the central or midway position, the top of the pan touches the ground and the portion H² of the bar H is allowed to free itself from the incision G¹. The team 85 is driven forward, and the slight drag of the tip of the pan on the ground is sufficient to upset or dump the pan, it coming into the position shown in Fig. 3. As soon as the earth or such like is all clear from the pan, the team is turned around facing in the opposite direction, and the pan drops again with the portion H² within the incision G¹. The lever is then thrown to the 90 upper or vertical position and the pan is locked clear of the ground. It will be understood that although I have spoken of the tip of the pan touching the ground 95 with the lever in the horizontal and the midway positions, yet with the lever in the horizontal position, the wheels can be lifted clear of the ground, thus allowing the pan to scrape. Throughout all operations the swivel wheel is directed by the operator from the seat. 100 It will be noted that there are no extending handles to be used in dumping, and by the simple swing lift the necessity of having extra men to aid in dumping is avoided.

In using the scraper to fill excavations, etc., a great deal of time is saved, by being able to dump directly 105 over the side of the excavation. The team can be driven so that the scraper comes to the edge and is dumped, the team remaining continuously on the road bed. In building through sloughs it is unnecessary for the team to go into the water and get their feet wet. 110

A second embodiment of my invention is shown in Fig. 5, in which the scraper can be described as a pull scraper, distinguishing it from the one hereinbefore described, which could be called a push and pull scraper. In this case the pan is supported in exactly 115 the same manner as in the other, but the drag bar is shortened, and just of sufficient length to allow for operation of the locking bar. Referring to the drawing, S is the drag bar and S¹ the locking bar, operated by the lever L, working in the quadrant J¹, as in the 120 before mentioned case. The lever operates the locking bar and locks the pan exactly as before. The swivel wheel P has not a hand wheel to operate it and it simply turns of its own accord. The bars E extend forwardly above the pan in practically the same manner as they pass to the rear, and have secured at the front a tongue O, which is pivoted by means of a pin O² to the forward ends of the bars. O³ are braces like those F, passing across and reinforcing the bars. In using this form of scraper it will be found a great deal 125 130

more convenient than that heretofore employed, on account of having the pan controlled by a single operator and embodying as it does the swing lift pan, doing away with a great deal of unnecessary labor.

5 Referring to Fig. 2 it will be noticed that the pan is dotted in a reversed or overturned position, with its edges lying on the side bars or framework E, and the bar H resting centrally on the bar C. It may be found convenient to throw it into this position when it is 10 desired to travel some distance before it is required to use the pan, as it is a great deal higher off the ground than in any of the other positions.

What I claim as my invention is:

1. A scraper comprising in combination a pan, a supporting bar straddling the pan and pivotally connected thereto, stub axles secured to the bar, carriage wheels on the axles, a draft frame pivotally swung on the axles, a drag bar, and means whereby the pan may be locked in an upper or lower position, as and for the purpose specified.

20 2. A scraper comprising in combination, a pan, a bar, straddling the pan, and having its free ends pivotally secured to the pan, below and forward of the center of its sides, stub axles secured to the bar, a set of carriage wheels on the axles, a draft frame swung on the axles, a drag bar 25 extending rearwardly from the draft frame, a V-shaped bar projecting from the forward face of the pan, and means whereby the said projecting bar may be locked in previously determined positions, as and for the purpose specified.

30 3. A scraper comprising in combination a pan, a bar straddling the pan, and having its free ends pivotally connected thereto, stub axles extending from the bar, carriage wheels supporting the axles, a draft frame swung from the axles, a drag bar extending from the draft frame, a 35 V-shaped bar extending from the end face of the pan, a swivel wheel, and means for locking the said V-shaped bar in predetermined positions, as and for the purpose specified.

4. In a scraper the combination with a pan, pivotally 40 supported from the carriage wheels, and the draft frame swung from the axles of the carriage wheels, of a hollow drag bar extending from the draft frame, a lock bar within the drag bar, a V-shaped bar projecting from the end face of the scraper, and means whereby the coöperation of the 45 lock bar with the drag bar locks the projecting bar in predetermined positions, as and for the purpose specified.

5. In a device of the class described, the combination with a pan pivotally supported from the carriage wheels and the draft frame swung from the axles of the carriage 50 wheels, of a hollow drag bar having a portion of its forward upper face notched away, a lock bar slidable within the drag bar and having a portion of its upper face notched away, a substantially V-shaped bar projecting from the

pan and adapted to be received at its angle within the notched portion of the lock bar and means whereby the co-operation of the lock bar with the drag bar locks the V-shaped bar in predetermined positions, as and for the purpose specified.

6. In a device of the class described the combination with the pan and wheel supporting bar, and the draft 60 frame swung from the aforesaid bar, of an extending drag bar, a swivel wheel at the rear end of the drag bar, a substantially V-shaped bar extending from the pan and normally extending outwardly beyond the front end of the drag bar, a swinging tongue secured to the rear end of the drag bar, and means whereby the V-shaped bar may be locked in predetermined positions, as and for the purpose specified.

7. In a device of the class described, the combination with the carriage wheels, the swing lift pan, the draft 70 frame and the drag bar, of a swivel wheel supporting the rear end of the drag bar, and a swinging tongue secured to the rear end of the drag bar, as and for the purpose specified.

8. In a device of the class described, the combination 75 with the pan, the wheeled bar straddling and supporting the pan, and the draft frame of a drag bar extending from the draft frame, a hand operated swivel wheel supporting the rear end of the drag bar, a swinging tongue secured in proximity to the rear end of the drag bar, a seat turning with the tongue and means whereby the operation of the pan may be controlled by the operator from the seat, as and for the purpose specified.

9. In a device of the class described, the combination 85 with the pan, the draft frame, the substantially V-shaped bar extending from the pan, and the hollow drag bar having a wedge-shaped recess in its upper face, of a bar slideable within the drag bar having a wedge-shaped recess in its upper face to receive the V-shaped bar at its angle and adapted to coöperate with the drag bar to lock the V-shaped bar in predetermined positions, as and for the purpose specified.

10. In a device of the class described, the combination comprising a pan, a wheeled bar straddling the pan and supporting it, a draft frame, a drag bar extending from the draft frame, a V-shaped bar extending from the pan, a swivel wheel supporting the rear end of the drag bar, a swinging tongue supported from the rear end of the drag bar, a seat turning with the tongue, a locking bar adapted to coöperate with the V-shaped bar and the drag bar to lock the pan in predetermined positions, a lever within range of the seat and operating the locking bar, a toothed quadrant in proximity to the lower end of the lever and a latch and a detent to the lever, as and for the purpose specified.

HENRY JAMES BICKLE.
